UNITED STATES PATENT OFFICE.

FRANK BERNSTEIN, OF NEW YORK, N. Y.

CLASP.

Application filed March 24, 1927. Serial No. 178,009.

This invention relates generally to fastening devices, and has more particular reference to a novel type of clasp for straps used on underwear, brassières, garters, suspenders, leather goods, and the like.

The invention has for an object the provision of an improved clasp which will act efficiently, and which can be manufactured and sold at a reasonable cost.

For further comprehension of the invention, and of the objects and advantages thereof, reference will be had to the following description and accompanying drawing, and to the appended claims in which the various novel features of the invention are more particularly set forth.

Referring to the drawing, forming a material part of this disclosure:

Fig. 1 is a plan view of a clasp constructed according to this invention.

Fig. 2 is a side elevation thereof.

Fig. 3 is a side elevation of a modification of the invention device.

Fig. 4 is a side elevation of another modification of the invention device.

Fig. 5 is a fragmentary enlarged view of a certain portion of the device shown in Fig. 4.

Fig. 6 is a vertical sectional view taken on the line 6—6 of Fig. 4.

The reference numeral 10 indicates the base of a body formed with a pair of vertical side lugs 11, a front inturned edge 12, and an aperture 13. A clamp body 14 has a front inturned edge 15 aligned with the edge 12, and a pair of side pintle pins 16 engaged in the lugs 11. A supplementary clamp body 17 has a pair of side pintle pins 18 engaged in the lugs 11, and a cam arm 19 abuttable against the clamp body 14. The supplementary clamp body 17 may be manually turned upwards about its pintle pins 18 and the cam arm 19 will release the clamp body 14. A strip of material 20 may then be inserted between base 10 and the clamp body 14, and thus clamped by depressing the supplementary clamp body 17. Another strip of material, not shown on the drawing may be inserted through aperture 13 and permanently sewed in this condition.

In the modification shown in Fig. 3, the base 10' is of sufficient length to accommodate two pairs of lugs 11', two clamp members 14', and two supplementary clamp members 17', each arranged as explained in the preferred form. With this arrangement

one strip of material 20' may be clamped at one end of the device, and another 20' at the other end.

In the modification shown in Figs. 4 to 6, the vertical side lugs 11' are resilient so as to be capable of bending as indicated by the dash dot lines in Fig. 6 without permanent injury. The supplementary clamp member 17' is cut as indicated by 21 to allow this bending. The pintle pins 18 have flanges 22 secured at the outer extremities, and these flanges prevent the vertical lugs 11' from bending further outwards than the vertical position. The pintle pins 18 are rotatable in eccentricities 24 having serrated edges 25 engageable in serrated apertures 26 of the lugs 11'. The pintle pins 16 similarly are formed with flanges 22 and eccentricities 24. In order that the clasp acts effectively for different thicknesses of material 20 it is necessary to adjust the eccentricities 24 properly. Pressing the lugs 11' together, the eccentricities 24 may be disengaged from the apertures 26 and turned to vary the distances between the supplementary clamp body 17, the clamp body 14, and the base 10. Upon releasing the lugs 11' they reengage the eccentricities, locking them in adjusted positions. The lugs 11' are formed with slots 28, and when the lugs are pressed together into the position indicated by the dotted lines in Fig. 6, the supplementary clamp body 17, and the clamp body 14 may be removed, by the pintle pins 18, 16 passing through these slots 28 as these parts are lifted upwards. This permits of retempering these parts, should they lose their temper during use.

While I have illustrated and described my invention with some degree of particularity, I realize that in practice various alterations therein may be made. I therefore reserve the right and privilege of changing the form of the details of construction or otherwise altering the arrangement of the correlated parts without departing from the spirit or the scope of the appended claims.

Having thus described my invention, what I claim as new, and desire to secure by United States Letters Patent is:

1. A device of the class described, comprising a base, a pair of resilient vertical side lugs formed therewith, clamping means, pintle pins on the sides of said clamping means, flanges secured to the extremities of the pintle pins, and eccentricities formed with serrated edges rotatably supporting the pin-

tle pins, the side lugs being formed with serrated apertures, and the eccentrics being adjustably engageable in the serrated apertures.

5. 2. A device of the class described, comprising a base, a pair of resilient vertical side lugs formed therewith, clamping means positioned between said lugs, supporting means on the sides of said clamping means, flanges 10 secured to the extremities of the said supporting means, and eccentrics formed with serrated edges rotatably supporting the said supporting means, the side lugs being formed with serrated apertures, and the eccentrics 15 being adjustably engageable in the serrated apertures.

3. A device of the class described, comprising a base, a pair of resilient vertical

side lugs formed therewith, clamping means, pintle pins on the sides of said clamping means, flanges secured to the extremities of the pintle pins, and eccentrics formed with serrated edges rotatably supporting the pintle pins, the side lugs being formed with serrated apertures, the eccentrics being adjustably engageable in the serrated apertures, and the said pair of side lugs being formed with slots communicating with the serrated apertures, so that when the side lugs are pressed together, disengaging the eccentrics from the lugs, the pintle pins may slip through the said slots in the side lugs. 20 25 30

In testimony whereof I have affixed my signature.

FRANK BERNSTEIN.
